DRIVING AND STOPPING MECHANISMS

Otto R. Haas, North Beverly, Mass., assignor to
 United Shoe Machinery Corporation, Borough
 of Flemington, N. J., a corporation of New
 Jersey

Application February 25, 1938, Serial No. 192,445

24 Claims. (Cl. 112—219)

The present invention relates to shoe sewing machines, and more particularly to improvements in a sewing machine of the type illustrated and described in inventor's co-pending application for 5 U. S. Letters Patent Serial No. 76,924, filed April 29, 1936, upon which Patent No. 2,148,197 issued February 21, 1939, having stitch forming devices and driving and stopping mechanisms under the control of a manually operated foot treadle for 10 either starting or stopping the stitch forming devices.

Shoe sewing machines in present commercial use in which the shoe is presented to a machine while held in the hands of the operator are arranged to be under constant control of the operator while sewing and to be brought to rest by the operator when a seam is completed, or at other times when the stitch forming devices operate improperly. Ordinarily a shoe sewing machine is started by pressure of the operator's foot on a control treadle and, when the machine is to be stopped, the pressure is released. In machines designed to operate at speeds much higher than ordinary, such as in the machine illustrated in the application above referred to, a number of cycles of operation may take place between the instant at which an improper operation occurs, and the time at which the pressure on the foot treadle is relieved. One or more further operations also take place while the machine is being stopped by the driving and stopping mechanisms. Unless the operator is exceptionally alert to breakage of thread, or to other improper operation, an excessive number of needle or awl perforations may be made in the work or the stitch forming devices may be damaged before the operator detects the difficulty. After the machine is stopped and again made ready for proper operation, the usual practice is to start the machine regardless of the alignment of perforations previously made in the work with the new work penetrating movements of the needle or awl, and as a result, the work along a substantial proportion of the seam is weakened by additional 45 perforations, and rendered unsightly in appearance.

The objects of the present invention are to provide a novel and improved high speed shoe sewing machine of the type indicated in which a 50 uniformly satisfactory seam is more easily formed than heretofore and in which the difficulties referred to are avoided, and more particularly for preventing an excessive number of stitching cycles of the machine between the occurrence of 55 an improper operation and the time the machine

comes to a full stop so that full attention of the operator may be directed towards properly presenting the work to the machine.

In the machine disclosed in the inventor's patent heretofore referred to, a thread cutter is provided, acting whenever the machine stops to sever the thread by cutting beneath the surface of the work. If for any reason it is necessary to stop that machine before the seam is completed, the thread may be severed and the surface of the work unnecessarily injured at an intermediate position in the completed seam. Thus, an additional injury may be made at the surface of the work. A further object of the present invention is to provide a thread cutter for a manually controlled shoe sewing machine arranged to operate only at the end of a completed seam, and to be held inoperative at all intermediate positions in a seam where the machine is likely to be stopped by reason of an improper stitching operation. 20

With these and other objects in view, the present invention relates to the provision in a shoe sewing machine having stitch forming devices actuated through driving and stopping mechanisms under control of a manually operated foot 25 treadle, of means acting automatically as soon as an improper stitch is made to prevent continued and unnecessary injury to the work, even though the operator fails to observe the difficulty. In the present embodiment of this feature of the invention, the stitch forming devices are stopped when the tension on the sewing thread fails to draw the auxiliary take-up to one side, as in regular sewing, and the treadle and the driving and stopping mechanisms are immediately disconnected. 30 35

The machine hereinafter described is also equipped with a thread cutter similar to that of the application referred to, acting automatically when the machine is stopped to sever the sewing thread, but means are provided in the present machine for preventing actuation of the thread cutter when the treadle is held depressed so that if the machine is stopped before the end of a seam is reached by disconnection of the treadle and the driving and stopping mechanisms, the sewing may be restarted without break in the thread after suitable adjustments are made. While this feature is particularly applicable to use with the novel features of the control means 40 for stopping upon failure of tension, it is not necessarily limited to such use, but is advantageous when applied to any sewing machine having treadle controlled driving and stopping mechanisms and an automatically actuated 45 50 55

thread cutter, in which the driving and stopping mechanism may be controlled to stop sewing by means other than release of the treadle.

Another feature of the invention relating to the auxiliary take-up which is also of general application to any sewing machine with or without a thread cutter, contemplates the provision of novel and improved means for causing the auxiliary take-up not only to maintain a yielding tension on the thread during sewing, but also to take up yieldingly and to hold within the machine at the end of a seam an extra length of thread for use in the first stitch of a new seam so as to prevent breakage or waste of thread in restarting the machine.

Other features of the invention include certain devices, combinations and arrangements of parts hereinafter described and claimed, the advantages of which will be readily understood by one skilled in the art from the following description taken in connection with the accompanying drawings in which Figure 1 is a view in front elevation, partly broken away and in section of the upper portion of a sewing machine embodying the features of the present invention, and illustrating the actuating parts in stopped positions; Figure 2 is a view in side elevation of the machine with parts partly broken away, as viewed from the right of Figure 1; Figure 3 is a similar view, looking from the left hand side of the machine; Figure 4 is a view on a slightly enlarged scale of some of the parts shown in Figure 3, and with the control connections shown in operating positions; Figure 5 is a detail view of some of the connections, taken on the line 5—5 of Figure 4; Figure 6 is a view in rear elevation, partly in section of the machine; Figure 7 is a view in front elevation on an enlarged scale of a portion of the machine including the main and auxiliary take-ups; Figure 8 is a view of the same parts shown in positions somewhat later in a sewing cycle than the positions indicated in Figure 7; Figure 9 is a similar view of the parts as shown in Figures 7 and 8 showing the positions assumed when the machine is stopped by failure of tension on the thread; Figure 10 is a view, partly in section of the parts shown in Figure 9, looking from the left hand side of the machine; Figure 11 is a detail sectional view, taken along the line 11—11 of Figure 9; Figure 12 is a detail view of the auxiliary take-up and some of the actuating mechanisms connected therewith, shown in section taken along the line 12—12 of Figure 1; and Figure 13 is a sectional view taken on the line 13—13 of Figure 4.

Except as hereinafter described, the various parts of the machine illustrated in the drawings are constructed and arranged to operate as in the lockstitch shoe sewing machine of inventor's patent above referred to. The machine is provided with stitch-forming devices including a curved hooked needle 2, a curved awl 4, a shuttle 5, a work support 6, a presser-foot 7, a main take-up 8 and a tension wheel 10. The stitch forming devices are actuated from a main sewing cam shaft 12 through connections which are the same as those embodied in the machine of inventor's patent above referred to, and will not be particularly described herein. Within the shuttle is a supply of locking thread, one end of which is indicated at 14, and the needle thread 16 passes from the tension wheel 10 around pulleys 18, 20 and 22 to the main take-up 8 before reaching the work. Between the pulleys 20 and 22 the thread passes over an auxiliary take-up 24 loosely mounted on a stud bolt 25 which also supports

the pulley 22 for rotation. The thread passes under the pulley 22, over the auxiliary take-up and under the pulley 20 so that the auxiliary take-up tends to hold thread yieldingly at one side of its normal path between the two pulleys except when a stitch is being set, at which time the auxiliary take-up yields up thread as shown in Figure 8.

The driving and stopping mechanisms are the same as in the machine of inventor's Patent No. 2,078,942 of May 4, 1937, and comprise a high speed treadle controlled clutch 26 (Figs. 1 and 2) for driving the sewing shaft, and an automatically controlled reversely driven low speed clutch, the driver of which is indicated at 28 and the driven member at 29. In stopping the machine the low speed clutch is first actuated and then rendered inoperative when the needle and awl are clear of the work, and a timing cam 30 is provided for this purpose. A cam lever 32 is vibrated by the cam 30 while the machine is in operation, and the lever is locked against movement when the machine is to be stopped. To start the machine in operation, the main driving clutch 26 is engaged through the action of a forked arm 34 connected at its upper end with the clutch and secured to a rock shaft 36 having an arm 38 to which the upper end of a vertical rod 40 is secured. The rod 40 is slidable in a perforated block 42 pivotally mounted on an arm 44 connected to one end of a shaft 46. The other end of the shaft 46 has an arm 48 to which the upper end of a treadle rod 50 is pivotally connected, and the lower end of the rod is connected to a foot treadle 52. When the treadle is depressed, a spring 51 on the rod 40 is compressed against a check nut on the rod 40 by downward movement of the block 42, and the clutch 26 is engaged. When the treadle is released, the clutch 26 is disengaged by means including springs 53 and 54 connected to the arm 44 and the arm 38, respectively. The arm 44 is provided with a hook shaped cam surface engaged by a roll on a lever 56 having an upstanding forked arm embracing a spool-like member at the end of a lock bolt 58, so arranged that when the treadle is depressed to start the machine, the lock bolt 58 will be withdrawn from an opening in the lower end of the cam lever 32 and when the treadle is released, the lock bolt will be allowed to engage and lock the lever 32. The parts so far described and the other stitch forming devices with their actuating mechanisms are the same as in the machine of inventor's application.

In the machine illustrating the embodiment of the invention, means are provided for disconnecting the treadle from the driving and stopping mechanisms whenever the tension on the sewing thread fails to draw the auxiliary take-up 24 to one side from its retracted position (Fig. 7) so that the machine will automatically be brought to rest. To urge the auxiliary take-up yieldingly towards its retracted position during sewing, the hub of the auxiliary take-up is surrounded by a coil spring 60, one end of which is held by a forwardly bent stop arm 62, and the other end of which is hooked around the auxiliary take-up arm (see Fig. 12). To limit the taking up movement of the auxiliary take-up, the auxiliary take-up arm carries a perforated plate 64 surrounding its hub and having a forwardly bent finger 66 arranged to cooperate with the stop arm 62 when the auxiliary take-up is retracted by the spring 60. The plate 64 is provided with a slotted por-

tion through which passes a screw 68 threaded into the auxiliary take-up arm, so that the retracted position may be adjusted. When the finger 66 attached to the auxiliary take-up rests 5 against the arm 62 during sewing, the forwardly bent portion of the finger lies in the path of a reciprocating rod 70 guided within a sleeve-like passage formed in a threaded bar 72 attached to the machine frame. The upper end of the rod 70 10 is pivotally connected to one arm of a lever 74 fulcrumed on a screw stud 76 which in turn is threaded to one end of an arm 78 fixed to a rock shaft 80 (see Fig. 12) extending rearwardly of the machine. The lever 74 is oscillated on the 15 stud 76 during each sewing cycle of the machine by connections including a link 81, as will be more fully described hereinafter, just as each stitch is set, so as to project the rod 70 into the path of the finger 66. During normal sewing 20 operations, movements of the auxiliary take-up by the thread draws the finger 66 yieldingly out of the way of the reciprocating rod 70, while each stitch is being set (Fig. 8). At this time the maximum tension is being applied to the needle 25 thread and if looseness occurs in the thread, the thread will fail to cause the auxiliary take-up to yield so that the rod 70 will engage the finger 66 and the rod will be held from reciprocating movement as shown in Fig. 9. When this occurs, the oscillation of the lever 74 about the screw stud 76 is stopped and the stud and the arm 78 are raised upwardly about the shaft 80 as a center, causing the shaft to be rotated. The rearward 30 end of the shaft 80 carries an arm 82 (see Figs. 4 and 6) connected with latch means for disconnecting the treadle rod and the driving and 35 stopping mechanisms.

The latch means for disconnecting the treadle from the driving and stopping mechanisms is best 40 shown in Figs. 4, 5, 10 and 11. Referring to these figures, the arm 48 to which the upper end of the treadle rod 50 is connected, is loose on the shaft 46, and at the end of the shaft there is a short arm 84, the free end of which is provided with 45 a shoulder cooperating with a latch lever 86 secured to a pin 88 rotatable in a lug on the arm 48, the pin serving as a fulcrum for the lever 86. The latch lever 86 is ordinarily held in alignment with and directly above the shoulder on 50 the arm 84, as shown in Fig. 4, by a spring 90 stretched between a pin on the latch lever 86 which extends through a slot in the arm 48 and a dog 92 pivotally mounted on the arm 48. In 55 this position of the latch lever, the arm 48, which is connected with the treadle and the arm 84 which is secured to the shaft 46 act together to control the driving and stopping mechanisms. However, when the reciprocating rod 70 engages the finger 66, as indicated in Fig. 9, the shaft 80 60 being rotated, a vertical link 94 connected at its upper end with the arm 82 on the shaft 80 causes one end of the dog 92 to engage an arm 96 on the pin 88 which supports the latch lever, thus causing the latch lever to move out of alignment with the end of the arm 84, as shown in Fig. 10. In this position of the latch lever the arm 84 is disconnected from the arm 48 so that the springs 53 and 54 cause the driving and stopping mechanisms to bring the machine to rest. 65 To actuate the dog 92 against the arm 96 the lower end of the link 94 is provided with a pin 98 engaging one end of the dog 92. The link 94 has a slot 102 at its lower end through which passes a screw 100 so that the link may move relatively 70 to the arm 48. The link 94 is also formed with

an upper rod-like portion passing through a sleeve 104 in the frame, and is provided with a cap member 106 to prevent escape of lubricating oil through the sleeve. To maintain the link 94 in lowered position, so that the latch lever may not accidentally be moved, the rod-like portion of the link is surrounded by a coiled spring 108 compressed between an under-surface of the frame and a shoulder on the link. 5

When the machine has been brought to rest 10 after disconnection of the treadle controlling connections, the connections will not be reset until the treadle is released. The timing of the machine is such that after the reciprocating rod 70 has been projected against the finger 66 to 15 stop the machine, it will be withdrawn from the finger during the final movements of the machine by the driving and stopping mechanisms so that the link 94 will be again lowered and the latch lever 86 permitted to engage the arm 84. This 20 engagement of the latch lever with the arm 84 occurs, however, after the arm has been moved above the lower end of the latch lever as shown in Fig. 10, so that the parts are re-latched only 25 after the arm 48 and the treadle have been released. If the cause of slack thread has been removed when the treadle is again depressed after being released, the machine will operate in the usual way, but if the difficulty has not been removed the machine will again be brought to rest 30 in the manner just outlined after the completion of a single sewing cycle of operation. 35

To reciprocate the rod 70 towards and from the path of the finger 66, the link 81 is connected at its uppermost end to an arm 110 formed integrally with the forward end of a shaft 112 parallel to the shaft 80. At the rearward end of the shaft 112 is an arm 114 connected to the lower end of a link 116, having at its upper end a slotted block 118 (see Figs. 3 and 4) forming a universal connection with one arm of a lever 120 rotatably mounted on a shaft 122. The lever 120 has an arm formed with a gear segment meshing with a gear segment on a cam lever 124 which corresponds with the cam lever 47 of the prior application. The cam lever 124 is fulcrumed loosely on a shaft 126 and is actuated by a cam slot 128 in a cam on the main sewing shaft 12. Cam slot 128 is so shaped that the rod 70 will reciprocate into and from the path of the finger 66 on 50 the auxiliary take-up arm 24 at a time in each sewing cycle that the stitch is being set by the main take-up. 55

The machine is also provided with a thread cutter constructed in a manner more fully described in inventor's Patent No. 2,148,197, and actuated across the path of the needle and awl against the work while on the work support 6. The knife 130 of the cutter is supported on an arm 132 secured at the end of a vertical shaft 134. The shaft 134 is given a rotary and reciprocating motion towards and from the work to impart a helical stroke to the knife 130, cutting the threads of the last stitch by penetrating the upper surface of the work as described in the 65 application. To actuate the knife, the shaft 134 is connected to a vertical rack 136 (see Fig. 2) meshing with a segment 138 on a horizontal shaft 140. On the shaft 140 is a second segment 142 meshing with a rack 144 having its rearward end 70 connected with a reciprocating link 146. The link 146 has at its free end an L-shaped slot 148 within which is a stud 150 on an actuating cam lever 152 pivoted at its lower end on a bolt 154 and provided with a follower 156 engaging a 75

slot in an actuating cam 158 loose on a continuously rotating auxiliary shaft 180 at the rear of the main sewing shaft, the cam being driven one revolution to actuate the cutter when the machine stops.

To cause the cam 158 to be rotated one revolution when the sewing shaft substantially reaches a position with the needle and awl disengaged from the work as the machine stops, there is a 10 one-revolution roller-type clutch 162 (see Fig. 2) connected to the cam which is held inactive during sewing by a pawl 164 rotatably mounted on a shaft 166 to move towards and from engagement with an abutment on the clutch. To withdraw 15 the pawl 164 from the abutment at the end of a seam so that the cam will be rotated, the shaft 166 also loosely supports a dog 168, two finger portions of which cooperate with a roll 170 when the sewing shaft 12 is reversely rotated by the 20 low speed driving clutch, and the dog 168 imparts a rotary movement in the proper direction to withdraw the pawl 164 just as the machine comes to rest.

If the machine of Patent No. 2,148,197 is 25 brought to rest, for any reason before the end of a seam to be completed is reached, the thread cutter will be actuated to sever the threads unless special adjustment is made, as hereinafter described, and an unnecessary cut will be made in 30 the surface of the work. When the machine is again started there will be a break in the line of stitching and an injury to the appearance of the work.

To avoid this difficulty, the prior machine is 35 equipped with a manual means including a control handle 172, arranged when set in proper adjusted position to prevent operation of the thread cutter. The handle 172 is pivoted on the frame of the machine and is connected by means 40 of a link 174 to an arm 176 secured to the outer end of a shaft 178. To the inner end of the shaft 178 is fixed an arm 180 (see Fig. 6) having a pin 182 sliding loosely in the slotted lower end of a link 184, the upper end of which is pivotally connected to the rearward end of the link 146 of the 45 cutter actuating connections. When the rearward end of the link 146 is held in lowered position the vertical part of the L-shaped slot 148 engages the stud 150 on the lever 152, so that the cutter will be actuated when the lever 152 is moved. To hold the cutter actuating link 146 in 50 lowered position, the link 184 is connected to one end of a tension spring 186, the other end of which is connected to the machine frame. When 55 the handle is moved rearwardly, the cutter actuating link 146 is raised until the stud 150 engages the horizontal part of the slot so that the cutter will not be actuated when the cam lever 152 is moved by the cam 158.

If the operator wishes to insure that the cutter of the machine disclosed in the application will 60 not operate in case the machine is stopped suddenly before the end of a seam is reached, the handle 172 may be kept in the rearwardly adjusted position until just before the seam is completed. In order to cause the cutter to be actuated, under these circumstances at the end of a seam, the handle 172 must be drawn forwardly 65 simultaneously with, or just before, release of the treadle. Otherwise the cutter will not be actuated until the machine is again restarted and stopped. This movement of the handle 172 requires an extra manipulation which is ordinarily 70 of greater inconvenience than that of severing 75

the threads with a hand knife at the end of a seam in the usual way.

As has been stated, the thread cutter in the present machine is held from operation if the machine is stopped by reason of automatically disconnecting the treadle from the driving and stopping mechanisms. To hold the thread cutter inoperative when the machine is thus stopped, connections are provided for preventing operation of the cutter when the treadle is held depressed. The cutter actuating cam 158 being caused to rotate only when the machine is stopped, the cutter can only be operated when the machine is stopped by release of the treadle in the usual way, and no cutting will occur if 15 the machine is stopped when the treadle is released after stopping.

The connections for preventing operation of the cutter act upon the slotted end of the cutter actuating link 146 and are so arranged that when 20 the treadle is depressed, the horizontal portion of the L-shaped slot 148 engages the stud 150 whether the handle 172 is in its rearward position or not. To permit the cutter actuating link 146 to be raised to this position when the treadle is 25 depressed, the lower slotted end of link 184 cooperates with a pin 188 (see Fig. 13) mounted on an arm 190 secured to the inner end of a shaft 192. The shaft 192 is rotatable in bearings alined with the bearings for shaft 178 so that pin 188 30 moves in the same arc as the pin 182. The pin 188 enters only partway into the slotted end of the link 184 so as not to interfere with the pin 182, the slot in the link 184 being long enough to permit the link 184 to be held in raised position by either of the pins 182 and 188 regardless of the position of the other. The shaft 192 has secured to its outer end an arm 194 (see Figs. 3, 4 and 6) connected to the treadle actuated arm 48 by a link 196. When the machine is stopped 40 by disconnecting the treadle from the driving and stopping mechanisms, the arm 48 is held in lowered position and the arm 84 only, which is secured to the shaft 46, is released.

The cam 30 for actuating the low speed driving clutch is so shaped that the machine is brought to rest after being reversely rotated with the main take-up 8 near the end of its taking up stroke, but spaced a short distance from the extreme limit of its taking up movement. When the work is withdrawn from the machine of the application after the operation of the thread cutter, the thread will adhere somewhat to the work so that the end of thread may be withdrawn with the work a short distance from the work support and a length of thread equal to the amount required by the take-up in completing its taking up stroke is drawn over the edge of the work support. When a new work piece is inserted in the machine and clamped by the presser-foot, the thread will also be clamped so that it will not be drawn back into the machine during the first stitch of a new seam. The amount of thread left on the work support, therefore, is wasted, being made up by an additional amount drawn from the supply when the machine is started. To prevent a length of thread being withdrawn from the present machine after stopping, equal to the amount required by the take-up in completing its taking up stroke, the auxiliary take-up 24 is actuated when the machine stops, in the present machine, to take up and hold yieldingly an amount of thread and to give up thread when the machine is restarted so that thread will be retained in the machine for use in completing 70 75

the first stitch of a new seam without further withdrawal from the supply.

To actuate the auxiliary take-up 24 at the end of a seam so that an extra length of thread will be held yieldingly within the machine while stopped for use in the first stitch of the new seam, connections are provided between the auxiliary take-up and the driving and stopping mechanism for changing the position of the stop arm 62. When the machine is running, the arm 62 is held in the position shown in Figures 7 to 9, so as to give the auxiliary take-up a limited range of movement, and when the machine is stopped the stop arm is lowered to the position of Figure 1 to increase the range of movement of the auxiliary take-up. The stop arm 62 is connected to a hub 198 (see Fig. 12) surrounding the bolt 25. The hub 198 also has extending from it an arm 200 pivotally connected to one end of a link 202, the other end of which is pivotally connected to an arm 204 secured to the forward end of a sleeve 206 surrounding the shaft 80 and having bearings in the machine frame. The sleeve 206 also has secured to its central portion an arm 208 pivotally connected to a slotted block 210 having a pivotal connection with a link 212 connected to a block 214 (see Fig. 4) similar to the block 210. The block 214 is pivotally connected with an arm 216, the arrangement providing for universal movement between the arm 216, the link 212 and the arm 208. The arm 216 is secured to the shaft 166 and to rock the shaft when the machine is stopped, the connections include a lever 218 secured to the shaft 166, a link 220 connected at its upper end to an arm of the lever 218 and at its lower end to an arm 222, a sleeve 224 (see Fig. 6) to which the arm 222 is fixed, and the lever 56 which is also secured to the sleeve 224. When the lock bolt 58 enters the opening in lever 32 to bring the machine to rest, the lever 56 rocks the shaft 166 and the connections described cause the stop arm 62 to be moved to the position of Figure 1, so that the spring 60, which actuates the auxiliary take-up, may rotate the auxiliary take-up further in a counterclockwise direction than occurs during sewing, thus yieldingly taking up an extra supply of thread. The extra supply taken up is adjusted to provide thread for the main take-up in restarting the machine. When the machine is restarted these connections return the stop arm 62 to the position of Figures 7 to 9 so that the extra supply is given up. If the thread cutter has been actuated when the machine is stopped, the end of thread in the first stitch of a new seam formed when the machine is restarted will be close to the work and will require no trimming. If the cutter is not operated, the yielding action of the auxiliary take-up will permit the work to be manipulated to a limited extent in order to relocate the work properly with respect to the stitch forming devices, and the seam may be continued without break in the thread or other irregularity.

The nature and scope of the invention having been indicated, and a machine embodying the features of the invention having been specifically described, what is claimed is:

1. A sewing machine having, in combination, stitch forming devices, driving and stopping mechanisms, means comprising a treadle and suitable connections for maintaining the driving and stopping mechanisms under the constant control of the operator during sewing to actuate and to stop the stitch forming devices at will, means acting automatically to render said connections ineffective to maintain continued actuation of the stitch forming devices when said devices operate improperly, and means for causing the stopping mechanism to stop the stitch forming devices when said connections are rendered ineffective.

2. A sewing machine having, in combination, stitch forming devices, driving and stopping mechanisms, means comprising a treadle and suitable connections for maintaining the driving and stopping mechanisms under the constant control of the operator during sewing to actuate and to stop the stitch forming devices at will, means acting upon failure of thread tension during a stitch forming cycle to render said connections ineffective to maintain continued actuation of the stitch forming devices, and means for causing the stopping mechanism to stop the stitch forming devices when said connections are rendered ineffective.

3. A sewing machine having, in combination, stitch forming devices, driving and stopping mechanisms, means comprising a treadle and suitable connections for maintaining the driving and stopping mechanisms under the constant control of the operator during sewing to actuate and to stop the stitch forming devices at will, and means acting automatically and independently of treadle movement upon failure of thread tension during a stitch forming cycle to cause the stopping mechanism to stop the stitch forming devices.

4. A sewing machine having, in combination, stitch forming devices, a main take-up, and a yieldingly actuated auxiliary take-up, driving and stopping mechanisms, means comprising a treadle and suitable connections for maintaining the driving and stopping mechanisms under the constant control of the operator during sewing to actuate and to stop the stitch forming devices at will, means connected to the auxiliary take-up for disconnecting the treadle from the driving and stopping mechanisms when the tension on the thread passing over the auxiliary take-up fails, and means for causing the stopping mechanism to stop the stitch forming devices when the treadle is disconnected.

5. A sewing machine having, in combination, stitch forming devices, driving and stopping mechanisms, means comprising a treadle and suitable connections for maintaining the driving and stopping mechanisms under the constant control of the operator during sewing to actuate and to stop the stitch forming devices at will, a thread cutter, and means for preventing actuation of the thread cutter when the treadle is held in a position to cause the stitch forming devices to be actuated.

6. A sewing machine having, in combination, stitch forming devices, driving and stopping mechanisms, means comprising a treadle and suitable connections for maintaining the driving and stopping mechanisms under the constant control of the operator during sewing to actuate and to stop the stitch forming devices at will, means acting automatically upon an improper operation of the stitch forming devices to cause the stopping mechanism to stop the stitch forming devices, a thread cutter, mechanism for actuating the thread cutter upon stopping of the stitch forming devices by manipulation of the treadle by the operator, and means for preventing actuation of the thread cutter upon stopping of the stitch forming devices by reason of an improper operation of said devices.

7. A sewing machine having, in combination, stitch forming devices, driving and stopping mechanisms, a thread cutter, power driven mechanism for actuating the thread cutter, means comprising a treadle and suitable connections for maintaining the driving and stopping mechanisms under the constant control of the operator during sewing to actuate and to stop the stitch forming devices at will, and treadle actuated connections for causing the thread cutter to be disconnected from its actuating mechanism when the treadle is depressed and to be reconnected to its actuating mechanism when the treadle is released.

8. A sewing machine having, in combination, stitch forming devices, driving and stopping mechanisms, a thread cutter, power driven mechanism for actuating the thread cutter, means comprising a treadle and suitable connections for maintaining the driving and stopping mechanisms under the constant control of the operator during sewing to actuate and to stop the stitch forming devices at will, means acting automatically upon an improper operation of the stitch forming devices to render the treadle ineffective to maintain continued actuation of the stitch forming devices, means for causing the stopping mechanism to stop the stitch forming devices when the treadle is rendered ineffective, and treadle actuated connections for preventing actuation of the thread cutter upon stopping of the stitch forming devices by reason of an improper operation of said devices.

9. A sewing machine having, in combination, stitch forming devices, driving and stopping mechanisms, a treadle for controlling the driving and stopping mechanisms, a thread cutter, power driven mechanism thrown into operation by the driving and stopping mechanisms in stopping the machine to actuate the thread cutter, means for rendering the driving and stopping mechanisms effective to stop the machine when the stitch forming devices operate improperly, and means for preventing operation of the thread cutter when the treadle is held in a position to cause the stitch forming devices to be actuated.

10. A sewing machine having, in combination, stitch forming devices, a main sewing shaft for actuating said devices, driving and stopping mechanisms, means comprising a treadle and suitable connections for maintaining the driving and stopping mechanisms under the constant control of the operator during sewing to actuate and to stop the stitch forming devices at will, a thread cutter, power driven mechanism thrown into operation when the sewing shaft reaches a predetermined position in stopping the machine, connections between the cutter and the power driven mechanism for actuating the cutter, and connections between the treadle and the cutter actuating connections for rendering the cutter inoperative when the treadle is in a position to cause the stitch forming devices to be actuated.

11. A sewing machine having, in combination, stitch forming devices, a main sewing shaft for actuating said devices, driving and stopping mechanisms, means comprising a treadle and suitable connections for maintaining the driving and stopping mechanisms under the constant control of the operator during sewing to actuate and to stop the stitch forming devices at will, a thread cutter, power driven mechanism thrown into operation when the sewing shaft reaches a predetermined position in stopping the machine, connections between the cutter and the power driven mechanism for actuating the cutter, connections

between the treadle and the cutter actuating connections for rendering the cutter inoperative when the treadle is in a position to cause the stitch forming devices to be actuated, and means for rendering continued pressure on the treadle ineffective to maintain continued actuation of the stitch forming devices when said devices operate improperly.

12. A sewing machine having, in combination, stitch forming devices including a main take-up, a yielding auxiliary take-up, a reciprocating member operated once during each sewing cycle of the machine, means for holding said member from reciprocating when the thread fails to cause the auxiliary take-up to yield, connections to said member for bringing the machine to rest when the member is held from reciprocating, a stop for limiting the movement of the auxiliary take-up during sewing, and means for moving the stop when the machine is being brought to rest to increase the yielding movement of the auxiliary take-up in a direction to take up thread.

13. A sewing machine having, in combination, stitch forming devices including a main take-up, an auxiliary take-up operating yieldingly through a limited range of movement to maintain tension on the thread, driving and stopping mechanisms for bringing the machine to rest, a stop for limiting the range of movement of the auxiliary take-up during sewing, and means for moving the stop to permit the auxiliary take-up to increase its range of movement in a direction to take-up an extra supply of thread when the machine is being brought to rest.

14. A sewing machine having, in combination, stitch forming devices including a main take-up, an auxiliary take-up operating yieldingly through a limited range of movement to maintain tension on the thread, driving and stopping mechanism for bringing the machine to rest, with the main take-up near the end of its taking up stroke, a stop for limiting the range of movement of the auxiliary take-up during sewing, and means for moving the stop as the machine comes to rest to increase the range of movement of the auxiliary take-up to take up an amount of thread equal to that required by the main take-up in completing its taking up stroke as the machine is restarted.

15. A sewing machine having, in combination, stitch forming devices, a main sewing shaft for actuating said devices, driving and stopping mechanisms, means comprising a treadle and suitable connections for maintaining the driving and stopping mechanisms under the constant control of the operator during sewing to actuate and to stop the stitch forming devices at will, a thread cutter, power driven mechanism thrown into operation when the sewing shaft reaches a predetermined position in stopping the machine, connections between the cutter and the power driven mechanism for actuating the cutter, connections between the treadle and the cutter actuating connections for rendering the cutter inoperative when the treadle is in a position to cause the stitch forming devices to be actuated, and manual means for preventing operation of the cutter in any position of the treadle.

16. A sewing machine having, in combination, stitch forming devices, a main sewing shaft for actuating said devices, driving and stopping mechanisms, means comprising a treadle and suitable connections for maintaining the driving and stopping mechanisms under the constant control of the operator during sewing to actuate and to stop

- the stitch forming devices at will, a thread cutter acting at the end of a seam to sever the thread close to the surface of the work in the machine, means for preventing actuation of the thread cutter at certain times when the machine is brought to rest, and yielding means for holding yieldingly a length of thread within the machine after stopping and for giving up said length of thread when the machine is started.
17. A sewing machine having, in combination, stitch forming devices, a main sewing shaft for actuating said devices, driving and stopping mechanisms, means comprising a treadle and suitable connections for maintaining the driving and stopping mechanisms under the constant control of the operator during sewing to actuate and to stop the stitch forming devices at will, means for yieldingly taking up a length of thread at the end of a seam, and means actuated upon restarting the machine for causing the said length of thread to be given up.
18. A sewing machine having, in combination, stitch forming devices, a main driving shaft for actuating said devices, driving and stopping mechanisms for bringing the shaft to rest at a predetermined angular position, a treadle for causing the driving and stopping mechanisms to actuate and stop the shaft, a thread cutter, power driven mechanism thrown into operation by the main shaft in coming to rest, connections between the cutter and the power driven mechanism for actuating the cutter, means for disconnecting the cutter actuating connections when the treadle is depressed, and means for causing the driving and stopping mechanisms to stop the main shaft while the treadle is depressed.
19. A sewing machine having, in combination, stitch forming devices including a main take-up, a yielding auxiliary take-up, a reciprocating member operated once during each sewing cycle of the machine, a finger actuated by the auxiliary take-up arranged to be engaged by the reciprocating member when the tension on the thread fails, means for bringing the machine to rest when the reciprocating member engages the finger, a stop to hold the auxiliary take-up at a position in which said member will engage the finger, and means for moving the stop when the machine is brought to rest to permit the auxiliary take-up to move in a direction to take up thread past the position in which said member will engage the finger.
20. A sewing machine having, in combination, stitch forming devices including a main take-up, a yielding auxiliary take-up, a reciprocating member operated once during each sewing cycle of the machine, a finger actuated by the auxiliary take-up arranged to be engaged by the reciprocating member when the tension on the thread fails, driving and stopping mechanisms, means for causing the driving and stopping mechanisms to bring the machine to rest when the reciprocating member engages the finger, a stop for the auxiliary take-up arranged to hold the auxiliary take-up at a position in which said member will engage the finger, and connections between the stop and the driving and stopping mechanisms for

moving the stop when the machine is brought to rest to permit the auxiliary take-up to move in a direction to take up thread past the position in which said member will engage the finger.

21. A sewing machine having, in combination, stitch forming devices, a main take-up, and a yieldingly actuated auxiliary take-up, driving and stopping mechanisms, a manually operated treadle for causing the driving and stopping mechanisms to actuate the stitch forming devices when the treadle is depressed, and means for disconnecting the treadle from the driving and stopping mechanisms during operation of the stitch forming devices when the tension on the thread passing over the auxiliary take-up fails, and thereafter for maintaining the treadle connected to the driving and stopping mechanisms for at least a single sewing cycle of the stitch forming devices after the treadle is released and again depressed, regardless of the tension on the thread.

22. A sewing machine having, in combination, stitch forming devices including a main take-up, an auxiliary take-up operating yieldingly through a limited range of movement to maintain tension on the thread, driving and stopping mechanisms comprising a high speed driving mechanism and a low speed driving mechanism having a vibrating lever and a lock bolt for engaging the vibrating lever after the machine is driven by high speed driving mechanism to bring the low speed mechanism into operation and the machine to rest, a stop for limiting the range of movement of the auxiliary take-up during sewing, and a connection acting when the lock bolt is brought into cooperative relation with the vibrating lever for moving the stop to permit the auxiliary take-up to increase its range of movement in a direction to take up an extra supply of thread when the machine is being brought to rest.

23. A sewing machine having, in combination, stitch forming devices, a cam shaft, driving and stopping mechanisms for said shaft, means comprising a treadle and suitable connections for maintaining the driving and stopping mechanisms under the constant control of the operator during sewing to actuate and to stop the stitch forming devices at will, and means actuated from the cam shaft, upon failure of thread tension during a stitch forming cycle, to render said connections ineffective and cause the stopping mechanism to stop the stitch forming devices.

24. A sewing machine having, in combination, stitch forming devices, a cam shaft, driving and stopping mechanisms for said shaft, means comprising a treadle and suitable connections for maintaining the driving and stopping mechanisms under the constant control of the operator during sewing to actuate and to stop the stitch forming devices at will, means actuated from the cam shaft when said devices operate improperly to render said connections ineffective to maintain continued actuation of the stitch-forming devices and cause the stopping mechanism to stop the stitch-forming devices.
